TRIMMING MACHINE

Warren S. Reynolds, Stratford, Conn., assignor to
 Remington Arms Company, Inc., Bridgeport,
 Conn., a corporation of Delaware

Application April 27, 1943, Serial No. 484,701

4 Claims. (Cl. 29—38)

1

This invention relates to automatic machinery particularly adapted for operating on metal articles and is especially applicable to turning operations. It is specifically disclosed, for illustrative purposes, for finishing articles such as the heads of cartridge cases. In quantity production of such articles it is necessary that accuracy be maintained and that the machine operating time be reduced as far as possible. In general, the present machine comprises a rotating turret which is indexed to various positions, said turret carrying a plurality of rotating chucks. The articles to be operated upon are fed, rotated to the tool stations and then ejected. The other objects of the invention will become apparent from the following description and illustrations which are merely exemplary.

In the drawings:

Fig. 1 is an end view of the machine looking toward the turret.

Fig. 2 is a side elevation view of the machine.

Fig. 3 is a side view partially in section.

Fig. 4 is a sectional elevation view taken in the direction 4—4 of Fig. 7, the main turret shaft being shown unbroken.

Fig. 5 is a sectional elevation view taken along the line 5—5 of Fig. 3.

Fig. 6 is a sectional elevation view of the locking means taken generally along the line 6—6 of Fig. 5. The slide has been broken away and part thereof is not sectional through the center line.

Fig. 7 is a sectional elevation view taken along the line 7—7 of Fig. 3.

Fig. 8 is a front elevation view of the turret and tool operating mechanism.

Fig. 9 is an enlarged side elevation view taken in the direction 9—9 of Fig. 8 showing the roughing tool.

Fig. 10 is an enlarged side elevation view in the direction 10—10 of Fig. 8 showing the finishing tool.

Fig. 11 is a fragmentary sectional view along the line 11—11 of Fig. 9 showing the adjustable roughing tool holder.

Fig. 12 is an enlarged sectional view of the tool feed mechanism looking in the direction 12—12 of Fig. 8.

Fig. 13 is an enlarged sectional view of the roughing tool taken in the direction 13—13 of Fig. 8.

Fig. 14 is an enlarged sectional view of the roughing tool operating mechanism taken in the direction 14—14 of Fig. 8.

Fig. 15 is an enlarged sectional view showing the operating connections between the roughing

2

tool operator and the tool rock shaft taken in the direction 15—15 of Fig. 8.

Fig. 16 is an enlarged sectional view showing the operating mechanism for the finishing tool taken in the direction 16—16 of Fig. 8.

Fig. 17 is a horizontal view partly in section of an alternative form of finishing tool taken in the direction 10—10 of Fig. 8.

Fig. 18 is an enlarged sectional view of one of the chucks.

Fig. 19 is a fragmentary sectional view along the line 19—19 of Fig. 17 showing the tools of Fig. 17.

Fig. 20 is a side view of one form of roughing tool.

Fig. 21 is an end view looking toward the dog mechanism of Fig. 6 and along the line of the axis thereof.

Fig. 22 is a cross section taken along the line 22—22 of Fig. 6.

In general, the present machine comprises a frame 20 having a turret 21 rotatably mounted on a shaft 22. Located on turret 21 are collets or chucks which comprise several parts and are identified generally by numeral 23. The chucks 23 are rotatably driven by suitable gearing. For purposes of illustration, cartridge cases will be used, but the invention is applicable to other articles. In the manufacture of cartridge cases, the base end of the drawn case must be finished and an extractor groove cut in the wall of the case adjacent the head. The groove is for engagement by feeding means of the gun and/or the extractor mechanism thereof so that the groove 35 must be accurately located and correctly formed.

A feed tube 24 feeds cases to the feeding means shown generally at 25. The specific details of the feeding means per se is disclosed in the copending application S. N. 473,065 filed January 21, 1943, now Patent No. 2,369,269, issued February 13, 1945. After a case is fed into a chuck at station A, the turret is indexed until a cartridge case is located at station C, at which point a roughing tool, shown generally in the tool holder 26, is 40 advanced and operates on the end and/or extractor groove of the case. Station B is provided as an additional station where other tools may be placed if desired to perform other operations on the case at this point. The turret at its next 45 indexing operation brings the chuck to station D where a finishing tool carrier, shown generally at 27, may operate on the case. At station E the case is ejected onto the delivery chute 28. The machine has a main driving motor at 29, located 50 within the frame, to operate the various cams 55

and parts in timed relation, as will be described hereinafter, to perform the functions as indicated. A motor 29 is provided for driving the spindles. The machine comprises a number of various parts which will be described in sequence.

Chucks

Referring now to Fig. 18, it is desirable that the chuck be constructed in such a manner as to assist in the feeding of the shells therein and to have parts so arranged that they may be interchanged with ease to provide for means to operate on articles or cartridge cases of different sizes and lengths. The chuck must be constructed so as to be easily manufactured and to maintain an article accurately in position while the tools are operating on the end of said article.

A cartridge case is shown at 30 engaged by the jaws 31 of the chuck 23. The jaws 31 are contracted by means of the sloping surfaces 32 on the chuck sleeve 33. The chuck may be of the usual split collet or contracting type. The chuck sleeve 33 is resiliently forced to the right (Fig. 18) by spring 34. Retraction of the chuck sleeve is performed by means of the semi-floating fulcrum levers 35. As the collar 36 is moved to the right, a locating pin 37 will engage one portion of a lever, said lever then being slidably pivoted on the fulcrum surface 38. This will move point 39 of the levers to the left to thereby engage surfaces 40 of the chuck sleeve and move the chuck sleeve to the left. This will compress spring 34 and release the spring jaws 31. By this construction it is not necessary to use a heavy fulcrum pin in the shell at a point where it would be difficult to fit the same. A fulcrum pin would also require enlargement of the parts at this point which is undesirable.

The chuck shell 41 is slotted at 42 and a slideable collar operating piece 43 is movable within this slot. The projecting portions 44 of piece 43 engage the collar 36. The chuck shell 41 has threads 45 cut thereon, said threads being interrupted by slot 42. Nuts 46 engage threads 45 and serve as a stop for movement of collar 36 to the left under the urging of spring 34. Chuck shell 41 has suitable bearings 47 carried between the shell and turret 21 in a well known manner. Chuck shell stop pin 48 may be used to limit movement of the chuck operating sleeve 33 and movement of the jaws 31 inwardly of the shell as the sleeve 33 is moved to the left to release the chuck. A threadedly attached cover 49 is provided which can be readily removed and the chuck or operating parts thereof exchanged for those of desired size if a different size piece is to be machined.

Gear 50 may be mounted on the chuck shell 41 and held in place by nut 51. The gear 50 is turned by means which will be described hereafter to rotate the chuck spindle assembly. An ejector plunger 52 is located within the jaws 31 and chuck sleeve 33. The ejector plunger 52 is moved by the ejector plunger operator 53 which in turn is moved by operating mechanism through aperture 54 in the collar operating piece 43. Movement of plunger operator 53 is transmitted through aperture 54 in the collar operating piece 43. Movement of plunger operator 53 is transmitted through spring 55 to ejector plunger 52, said spring being yieldable in case of a jam in the chuck. Pin 56 and collar 57 serve to limit movement of the operator 53 relative to ejector plunger 52. The forward end of the ejector plunger 52 has a hemispherical portion 58 which

will serve to guide a hollow tubular article, such as a cartridge case, into position during the feeding operation. The spindles turn in the direction indicated in Fig. 8.

Chuck spindle drive

The chucks are rotated at all times while the machine is operating and are driven by the motor 29 through drive shaft 209 (Fig. 5). Gear 210, located on the drive shaft 209, meshes with gear 211 (Figs. 3 and 5). Gear 211 is connected to sleeve 212 which encircles shaft 22, there being bushings 213 and 214 located between the sleeve 212 and the main shaft 22. Gear 211 may be held in place by means of lock nut 215 and key 241. A key slot is formed in which key 241 is held from endwise movement by pin 216. The gear is forced against flange 242 by turning lock nut 215 on threads 243. Gear 211 may be of the helical type, if desired, so as to pull the sleeve to the right and thereby take up end play constantly in one direction. A spacer 217 is provided to assist in properly locating sleeve 212 in conjunction with the upstanding flange of bushing 214. In the construction shown the sleeve is accurately held longitudinally. On the end of the sleeve 212 opposite to gear 211 there is a helical gear 218 (shown broken away above the main shaft) which meshes with chuck gears 50. As shown, gears 218 and 50 may be of the helical type with the helix direction so arranged that all play in the chuck bearings will be taken up to the left due to the thrust on the chuck gears which tends to draw the chuck assembly to the left (Fig. 3). By this means, the chuck will be located to the left and the movement of a case therein will not affect the position thereof in the turret. Thus the case will be accurately located each time which is desirable in precision quantity production.

As set forth above, the description of the feed mechanism is given in detail in said Patent No. 2,369,269. In summarizing, articles are fed from tube 24 into the chuck by means of a suitable carrier (not shown) which takes the articles from the inclined position and places them in a horizontal position. The feed rod 59 (Figs. 1 and 3) reciprocates in timed relation and moves a case from said horizontal position into a chuck located at the feed station. As described in said copending application (but not shown in detail herein) a feed member provided with a side opening aperture oscillates so as to carry a case from the inclined feed tube 24 to a horizontal position. At the horizontal position the article is discharged from the aperture onto a platform (not shown), the platform being reciprocated by the feed rod 59. The platform has a plunger thereon. The article is held in this horizontal position so that the platform slides thereunder until the end of the plunger is reached, at which time the case falls in front of the plunger and as the plunger is moved toward the turret, the article is carried into a chuck. These details are not shown inasmuch as they are described in said copending application.

The feed rod 59 is reciprocated by means of cam surfaces on the main cam drum 60 (Fig. 3) which is mounted on cam shaft 61 supported in the main frame of the machine by bearings 62 and 63. Bearing 63 is supported by the frame dividing wall 116. The cam shaft is driven by pulley 64 (Fig. 3) from the main operating motor 290 (Fig. 2). The motor 290 is not shown as it is located within the frame. As shown, pulley 64

may also serve as a handwheel. Feed rod operating lever 65 is pivoted at 66 and has a roller 67 which is engaged by the cam surfaces 68 on the cam drum 60. Motion thereof is transmitted through links 69 to block 70. Spring 71 abuts block 70 and collar 72 at its other end on feed rod 59. Spring 71 normally holds block 70 against feed rod collar 73 and thus the counter-clockwise rotation of the feed rod operating lever 65 will be transmitted to the feed rod 59 through spring 71 and collar 72. In the event there is a jam or stoppage which prevents feed rod 59 from moving to the left, spring 71 will be compressed and no damage will be done. A switch operator 74 is pivoted at 75 on block 70. As the spring 71 is compressed, block 70 will separate from collar 73 and surface 76 will coact with the switch operator 74 and cause the same to move upwardly, thereby contacting plunger 77 and operating a suitable microswitch 78 to stop the machine. The switch 78 may be placed in the circuit of the motor 290 in any of the usual manners. It is thus seen that the cam surfaces 68 on cam drum 60 will cause oscillation of feed rod operating lever 65, which in turn, will reciprocate feed rod 59 and move articles into a chuck.

Chuck opening and closing

In order for the article to be fed into the chuck and ejected therefrom, it is necessary that chucks be opened at the stations where these operations are performed, namely, stations A and E of Fig. 1. The chuck opening mechanism will be described specifically for the work ejecting station which is shown in Fig. 3. The chuck opening mechanism for the feed station is identical thereto with the exception that the ejection plunger is omitted. A hollow reciprocable actuator 79 is carried in bearing 80 of the main machine frame. A thrust bearing 81 is located on the end thereof, which contacts the sliding piece 43 of the collet operating mechanism. The reciprocable operator 79 is screw threadedly engaged with the crosshead 82. Adjacent the screw threaded portion there is a slot 83 and a screw 84 which may be tightened up so as to hold the reciprocating operator 79 in position after it has been adjusted therein. The crosshead 82 is pivotally connected at 85 by means of pivot pin 86 to the chuck operating lever 87 (Figs. 3 and 7). The upper end of lever 87 is bifurcated at 88 (Figs. 3, 4 and 7) and slidably engages the oscillatable block 89 which is pivotally connected at 90 to the frame of the machine. The lower end of lever 87 has a cam roller 91 which is engaged by the cam surfaces 92 of the main cam drum so as to reciprocate the crosshead 82. In this manner a straight line motion is given to the cross head 82 and the bifurcated end 88 may slide on the oscillatable block 89 as the cam surfaces 92 cause oscillation of the chuck operating lever 87. The reciprocable chuck actuator 94 for the feed station is similar to that just described but is not shown in Fig. 3 except for the threaded portion 93 and a small portion 94, which is broken away, so as to simplify the drawing. As the lever 87 is oscillated, motion is transmitted to the cross head 82 and from there to chuck actuators 79 and 94. These in turn transmit motion to the sliding piece 43 through the thrust bearings 81 so as to release the chucks.

Work ejecting mechanism

An ejector actuator rod 95 is located within the chuck actuator 79. Ejector actuator 95 is re-

ciprocated by means of ejector actuating lever 96 which is pivoted at 97 and has a cam roller 98 thereon which is operated by cam surfaces 99 of the main cam drum 60. The end of ejector actuator 95 advances at the proper time and enters the aperture 54 (Fig. 18) to engage plunger operator 53 which in turn ejects the case through ejector plunger 52 from the chuck as the chuck is opened. The ejector plunger and operators 52 and 53 remain in their forward position as the turret is indexed to the feed station. Then when an article is fed into the chuck, the rounded end 58 of the ejector plunger 52 assists in guiding the new article into place and the plunger and operators 52 and 53 are moved to the left by the new article.

Turret indexing

The turret is indexed by means of the Geneva escapement mechanism which includes the star wheel 100 (Figs. 3 and 7). Cam roller 101 located on the end of the main cam engages the apertures 102 of the star wheel and causes the main turret shaft 22 to be indexed the correct amount, the turret being unlocked.

Turret locking

The turret is locked by means of a dog 103 (Fig. 5) which is advanced into slots 104 (Figs. 3 and 5) in the external surface of the turret. These slots may be located in adjustable or removable plates 105 which are held in place by screws 106. The dog is advanced by means of spring 107 (Fig. 6). The tension of spring 107 may be adjusted by means of screw 108. The dog is retracted at the proper time by turret locking cam 109 which causes oscillation of the lock operating levers 110 and 110' which are mounted on shaft 111, said levers being connected by hub 115. A cam roller 112 is provided on arm 110. The arm 110' is connected to the lock operating slide 113 by means of stud 114. The lock slide 113 is slidable in a groove 221 (Figs. 21 and 22) cut in the slide carrier 228. Slide carrier 228 is held in place on the main frame by means of machine screws 229. The adjusting screw 108 is mounted in the head of the carrier 228 and may have a pilot 230 to assist in guiding the spring 107, said spring being located in an aperture 231 in the slide 113. The slide 113 is held in place by means of slide retaining bars 232 and 233. Slide retaining bar 232 may be fastened to carrier 228 by means of screws 234 and slide retaining bar 233 may be held in place by screws 235 and locating pin 236. The stud 114 engages a square bushing 237, said bushing being shown broken away along its center line in Fig. 6. The bushing 237 is located on the slide by means of a locking block 238 which is fastened to the slide by means of screw 239 and locator pin 240.

The turret indexing and locking is thus accomplished by means of the cam roller 101 entering the apertures 102 of the star wheel 100 and turning the same. Previous to this the locking dog has been withdrawn from slot 104 so as to allow the turret to turn. Upon completion of the turret movement cam 109 will have been so rotated as to allow re-engagement of the locking dog with the succeeding slot 104.

Tool operating means

A tool operating rock shaft 120 (Figs. 3 and 8) is oscillated by a cam on the end of the main operating cam drum 60 through roller 121 and tool shaft operating lever 122. Oscillation of

shaft 120 causes a rocking movement of the bell crank lever 123. (Figs. 8, 12 and 15.)

The operation of the roughing tool at station C first will be described. There is an upstanding arm 124 carrying a stepped stud 125 on which is mounted a block 126, said block 126 being slideable within the guide 127. Guide 127 is attached to arm 128 by means of nut 129 and pin 130. It is to be noted that Fig. 15 is a section looking in the direction 15—15 of Fig. 8, the drawing having been turned on the sheet so that the shaft 120 is shown in a vertical position instead of a horizontal position as it actually is in the machine. This is done for convenience in order to properly correlate Figs. 14, 15 and 16, which are cross sections, taken in the directions indicated, of the tool operating linkage. As the shaft 120 oscillates, the upstanding portion 124 will oscillate, which in turn will cause oscillation of arm 128 about its pivot 131.

Arm 128 pivots at 131 about an opposed conical surface two-part telescoping adjustable journal. There are two outwardly diverging conically shaped bearing surfaces 132 and 133 mounted on the frame of the machine. The journal which oscillates cooperatively with these conical bearing surfaces comprises two opposed conical surfaces carried by telescoping parts. One conical surface is integral with the head 135 of the lever arm 128. The other conical surface opposed thereto is integral with the telescopicable portion 134 of the journal which telescopes within the head 135 by fitting into the aperture 201 located in head 135. The portions 134 and 135 may be adjusted longitudinally of each other by means of varying the thickness of spacer ring 141. The screw 131 and washer 137 serve to hold 134 and 135 together through spacer ring 141. A key is provided at 138 for preventing relative rotation between 134 and 135. The key may be of the three-part "Presto" type if desired. As the adjusting screw 131 is tightened, the conical surfaces of 135 and 134 are moved closer together so as to tighten the journal between the conical surfaces 132 and 133. Operating arm 139 is attached to portion 134 by means of screws 140. By this means, lost motion can be controlled so as to insure accuracy in tool movement. A suitable sealing ring 142 of metal, leather or some other substance, may be employed to prevent chips or powdered material from entering the bearing and thus spoiling the bearing surfaces of the journal. The sealing ring 142 may have a metal backing 244 which is pressed inwardly by a plurality of springs 245.

Operating arm 139 has attached thereto a tool holder shown generally at 143 (Figs. 8, 9 and 13). The tool may be of the conventional circular type (Fig. 20) having a cut out portion 202. It is to be noted that Fig. 20 is taken in a direction looking to the left in Fig. 9. It is to be understood, of course, that other types of tools may be used.

A carrier block 144 is mounted on operating lever 139 by means of locking screws 145 which may be tightened to hold the block in place, adjusting slots being provided. The vertical position of the sliding block 166 may be adjusted by means of adjusting screw 146 after loosening locking screws 145. The tool is carried on a shaft 147 having a nut 148 thereon. The tool 149 is pinned to a plate 150 (Figs. 11 and 13) by pins 203. The tool may be adjusted for angularity by means of set screws 151 which are mounted in 144. The plate 150 has shoulders 204 cut thereon which cooperate with screws 151 for ad-

justing the angular position thereof. In this manner, the cutting edge 152 (Figs. 9 and 20) of the tool 149 may be adjusted.

As the rock shaft 120 is oscillated, the arm 139 will be oscillated. The tool 149 is thus oscillated about the pivot 131 so that it will engage the shell 153 and cut the desired grooves therein.

A plate 154 (Figs. 8 and 15) is mounted on the stud 155, said plate serving as a fastening for one end of the spring 156. The other end of spring 156 is mounted on the link by stud 205. This is done so as to take up all slack in the pivot pins and other surfaces before the tool starts to cut.

The finishing tool is operated by the mechanism about to be described. Link 157 is pivoted to arms 158 and 123. Arm 158 pivots at 165 about an opposed conical surface two-part telescoping adjustable journal similar to that described for pivot 131. The bearing comprises two outwardly diverging conically shaped bearing surfaces 161 and 162 mounted on the frame of the machine. The journal which cooperates with these conically shaped bearing surfaces has opposed conical surfaces carried by telescoping parts. One conical surface is integral with the head 163 of the lever 158 and the other conical surface opposed thereto is integral with the telescopicable portion 164 of the journal which telescopes in the head 163 within aperture 206 thereof. The head and telescopicable portion may be adjusted longitudinally of each other by means of varying the thickness of washer 169. The screw 166 and washer 167 serve to hold 164 and 163 together through spacer ring 169. A key is provided at 207 for preventing relative rotation between the head 163 and portion 164. Operating arm 171 is attached to telescopicable portion 164 by means of screws 208. In this manner it is possible to closely adjust and eliminate lost motion from the journal in a critical portion of the linkage for accurate movement of the tool. Sealing ring 170 is provided for preventing foreign material from getting into the pivot bearing and has a metal backing plate and springs similar to that described for Fig. 14.

Operating arm 171 has attached thereto a sliding plate 172 which is longitudinally adjustable on said operating arm. Adjusting screws 173 and 174 are located in elongated slots so as to provide for longitudinal adjustment of the adjustable plate 172. Pin 176 may be tapered and have adjusting and lock nuts 198 thereon. The tool 177 (Figs. 8, 10 and 16) is carried in the slot 178 of the plate and clamped in place by means of clamp 179 and screw 180. The tool 177 may be adjusted by means of the screw threaded member 192.

Adjustment of the plate 172 on arm 171 toward and away from the face of the chuck is effected by means of adjusting screw 181 carried in an aperture 182 (Fig. 10) of the bracket 183 on operating arm 171. The pin 184 and mating groove 185 in the shank of the screw 181 hold the screw 181 from longitudinal displacement in the bracket 183. Screw threads 186 are provided in the plate 172. By turning screw 181, the plate 172 is adjusted longitudinally on the arm 171 so as to properly locate the finishing tool relative to the head of the cartridge case to be finished.

As shaft 120 is oscillated, the arm 139, through arm 123 and link 157, will be oscillated and the finishing tool 177 will be carried into or across the head of the case being operated upon so as to give a finishing cut thereon.

It is to be noted that the lever arms are of different lengths so that the amount of oscillation

of the finish and roughing tool will not be the same and can be varied in accordance with the lengths of lever arms used. In the particular arrangement shown, the finishing tool will be given a greater travel than the roughing tool relative to the cases being finished. A spring 187 has one end fastened at 188 to lever 123 and one end 189 to arm 158 so as to take up slack in the pivot pin and other surfaces before the tool starts to cut.

An alternative type of tool is shown in Figs. 17 and 19. When a tungsten carbide tool is to be used it is difficult to cut the desired contour therein if a sharp corner is required. In order to trim the groove of a cartridge shell and put the exterior chamfer on the head it is necessary to provide two tools. This may be done by the tool holder arrangement shown in Figs. 17 and 19. The plate 193 is hinged on the hinge pin 176, which is carried by the sliding plate 172, similar to that previously described for Fig. 10. The adjusting screw shown at 181 is carried on the bracket 183. The tool for finishing the extractor groove of a cartridge case is shown at 194 and the tool for finishing the chamfer on the end of the cartridge is shown at 195. These tools are held in position by the clamping plates 196 and 197 which are locked in place by screws 198 and 199. In Fig. 19 may be seen a portion of a cartridge case at 200 with the groove finishing tool 194 and the head chamfering tool 195.

Oiling system.

One type of oiling system which may be employed includes a pump 220 (Figs. 3 and 7) which is driven from cam 221 located on the end of the main cam drum 60. A bell crank lever 222 serves to transmit the motion from cam 221 to pump 220 in a conventional manner. An oil strainer 223 may be provided through which the oil is pumped to the various bearings by way of oil manifold 224. A typical oil connection to a bearing is shown at 225. A level indicator 226 of the conventional type may be provided.

Summary

Shells are fed to the machine through feed chute 24 and by means of reciprocation of feed rod 59 by cam 68 are fed into a chuck located at station A. Previous to this, the chuck at station A has been opened by reciprocation of crosshead 82 by means of cam 92. The crosshead 82 then moves to the left allowing the chuck to close on the shell which then rotates rapidly with the chuck. The turret is then indexed twice until it reaches station C. At this point the tool operating rock shaft 120 is oscillated causing roughing tool 149 to be oscillated counter-clockwise (Fig. 8) about its pivot 131. This moves the tool into contact with the rotating shell and causes a roughing cut to be made thereon. The turret is then indexed to station D and at this point the next oscillation of tool rock shaft 120 causes movement of the finishing tool about its pivot 165 to move the finishing tool 177 counter-clockwise about said pivot and cause a finishing cut to be made upon the shell. At the next indexing of the turret a shell arrives at station E where actuation of crosshead 82 will open the chuck as previously described for the feed station. Crosshead 82 operates to open two chucks at a time through reciprocating operator 79 (ejection station) and reciprocation of operator 94 (feed station). When the chuck is open at the ejection station, ejection cam 99 will cause movement of ejector actuator rod 95 to the right (Fig. 3)

which will contact operator 53 and in turn will move ejector plunger 52 to the right and eject the shell from the chuck. The spring 55 may be partially cocked in this operation so that when friction between the shell and chuck is overcome the shell will be forcefully ejected outwardly and away from the chuck.

What is claimed is:

1. In a machine; a frame; an indexably rotatable turret carrying a plurality of chuck spindles; an ejection and feeding station; and means for simultaneously opening said chucks at said ejection and feeding stations including a cam, a pair of slideable operators for opening said chucks, a crosshead joining said operators, a lever pivotally connected to said crosshead, the fulcrum end of said lever having a floating connection with said frame and the opposite end of said lever engaging said cam for operating the lever and crosshead whereby the crosshead is given a substantially rectilinear motion.
2. In a machine; a frame; an indexably rotatable turret carrying a plurality of chuck spindles; an ejection and feeding station; means for opening said chucks at said ejection and feeding stations including a pair of slideable actuators for opening said chucks, a crosshead to which said actuators are adjustably fastened; a lever pivotally connected to said crosshead, the fulcrum end of said lever having a rotatable and slideable connection relative to said frame and the opposite end of said lever engaging a cam for operating the lever and crosshead, whereby the crosshead is given a substantially rectilinear movement; an ejector plunger in each of said chuck spindles; an ejector plunger operator slideable within the slideable chuck opening actuator at the ejection station; and means to operate said ejector plunger operator.
3. In a turret type machine having a plurality of chuck spindles; a pair of bell cranks mounted on said machine; a pair of sets of tools each adjustably mounted on an arm of one of the bell cranks to operate on work carried by said spindles; means to operate said tools comprising a cam operated rock shaft, a two-armed crank on said rock shaft, a sliding block connection between one arm of said two-armed crank and the bell crank on which one of said sets of tools is mounted and a link connection between the other arm of said two-armed crank and the bell crank on which the other of said sets of tools is mounted, the ratio of said connections being such that the tools are moved different distances at different rates by said rock shaft.
4. In a machine; a turret having a plurality of rotatable chuck spindles with interchangeable collets; a chuck shell for each collet; an actuator reciprocable within each shell relative to and cooperating with a collet for contracting the same, each of said collets having an ejection plunger aperture and an interchangeable, telescoping ejection plunger assembly, spring extended to a limited extent and slideably mounted in said aperture for axial floating movement therein limited by the collet and said actuator, said plungers having rounded ends for yieldably engaging a piece of work as it is being fed into a collet; caps engaging said shells for removably holding said collets in a position engageable by said actuators; feed and ejection stations for said machine; chuck opening means at said feed and ejection station each including a plunger and members cooperating with said actuator to operate any of the interchangeable collets; an operator at the

11

ejection station for moving any of the interchangeable ejection plungers to eject an article from an open chuck; means to indexably rotate the chuck from the ejection station; and means to feed an article into the chuck at the feed station, said article sliding the ejection plunger assembly against the actuator in a direction opposite to ejecting movement and slightly telescoping the spring extended assembly.

WARREN S. REYNOLDS.
